UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,987, dated July 1, 1890.

Application filed April 15, 1890. Serial No. 348,109. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 The drawing shows a side elevation of a cane or umbrella handle embodying my new design.

A is the upwardly-extending body part, and terminates at the top in a crook B and a rearwardly-extending excrescence E. The under part of the crook and the adjacent side of the body part A are made with a series of depressed portions C and are plain. The upper portion D of the crook is also plain; but where 15 it unites with the parts C it is ornamented or shaded to make a contrast, and the upper portions of the parts C extend slightly outward from the part D. The part H of the body por-

tion A is also plain, and, as in the case of the part D, is separated from the portions C by 25 ornamental or shaded work. At the upper portion of this part H there is a crook G, acting as a support for the excrescence E. The lower portion of the depressions C on the body part A terminate in the spiral I. The lower 30 portion of the body part A is relieved by a base-band F of ornamental work.

The handle is made of any suitable material.

Having now described my new design, what 35 I claim as new, and desire to secure by Letters Patent, is—

The design for umbrella or cane handles, substantially as herein described and shown.

In testimony of which invention I have 40 hereunto set my hand

HENRY O. SCHMIDT.
